UNITED STATES PATENT OFFICE.

LEWIS WATSON EGGLESTON, OF APPLETON, WISCONSIN.

FLUSHING DEVICE FOR WATER-CLOSET BOWLS AND THE LIKE.

No. 858,168.

Specification of Letters Patent.

Patented June 25, 1907.

Application filed September 7, 1905. Serial No. 277,328.

To all whom it may concern:

Be it known that I, LEWIS WATSON EGGLESTON, a citizen of the United States, and a resident of Appleton, in the county of Outagamie and State of Wisconsin, have invented a new and Improved Flushing Device for Water-Closet Bowls and the Like.

This invention relates to flushing devices, and it consists substantially in the details of construction and combinations of parts hereinafter more particularly described and pointed out in the claims.

The object of the invention is to provide devices of the character referred to which are simple in construction and comparatively inexpensive to install, besides being thoroughly effective and reliable in operation, and possessing the capacity for long and repeated service.

20 The above and additional objects are attained by means substantially such as are illustrated in the accompanying drawings forming a part of this specification, in which similar characters of reference indicate corresponding parts in all the figures, and in which

Figure 1 is a broken part sectional view of flushing-devices embodying my improvements, the normal positions of the operative elements thereof being shown in full lines, while the dotted lines represent substantially the positions occupied by said elements at about the time of completion of the siphoning of the water from the containing-tank therefor; Fig. 2 is a similar view, representing in full lines the positions occupied by some of the operative elements after being actuated to open the controlling valve for the structure, the dotted lines showing the position of the float and connections therefor at about the time the water in the tank reaches the height necessary to enable the siphoning of the same from the tank to take place; and Fig. 3 is a top plan view in detail.

45 Before proceeding with a more detailed description, it may be stated that in the form of my improvements herein shown, I employ the usual water-tank mounted at the desired height for effective operation of my improved flushing-devices, upwardly through the bottom of which extends the usual water-supply pipe for the tank, having at the upper end thereof a specially constructed valve-casing in which is located a specially con-

55 the water is discharged into the tank. Cooperatively organized with said nozzle or injector, and normally closing the same, is a specially constructed plug-valve having slide- 60 able movement within said casing, and mov- ably connecting with which is a specially constructed actuating lever therefor, through the medium of which said valve is caused to open the outlet of the nozzle or injector, and again close the same, as will presently be ex- 65 plained. A specially constructed controlling member is employed for said lever, intermediate of which and a co-operating float are other members of special construction, it being understood that my improved flush- 70 ing devices are primarily actuated through the medium of a pull-chain in the ordinary way.

75 Reference being had to the drawings by the designating characters thereon, 1 represents a water-tank mounted at a suitable elevation above the water-closet bowl (not shown) or the like to be flushed, the same being of any suitable material and dimensions, and either open or closed at the top, as 80 desired. Extending upwardly through the bottom 2 of the tank, at 3, is a water-supply pipe 4 for the tank, leading from any suitable source, and which, as shown, is provided at the upper end thereof with a casing 5, extending substantially at right-angles thereto, the same being open at the inner end thereof. Leading from the upper end of said supply pipe 4 is a nozzle or injector 9, preferably conical toward the outlet thereof, while located 85 within the casing 5, at its said open inner end, is a slideable plug-valve 10, having at the operative face thereof (disposed before the outlet of the nozzle or injector) an elastic cushion or packing 11, of suitable material, 90 as rubber, and at its inner end an extension 12 having a vertical opening 13 therethrough, between the sides of which works a swinging lever 14, the lower end of the shorter arm 15 of which is pivoted at 16 to the end of an arm 17 extending from the lower section 7 of the valve-casing 5, and the end of the longer arm of which is preferably somewhat enlarged and formed with an angular slot 18 therein, the branches of which occupy vertical and 100 horizontal positions, respectively, in the normal (vertical) position of said lever. Working in said angular slot 18 in the end of the longer arm of said swinging lever 14, is a pin 105 or boss 19, carried by a normally horizon- 110

2 tally-disposed member 20 (herein preferably shown as comprising duplicate parallel parts) provided near the outer end thereof with a weight 21, while movably connected at 22 to the inner end thereof is the upper end of a downwardly and inwardly turned link 23, pivoted at 24 to the inner end of an arm 25, extending from the upper section 6 of the valve-easing 5, and to the lower end of which is connected the rod 26 of a float 27, as shown. Movable connecting with the outer end of the said member 20, is a link 28, having movable connection at 29 with the inner end of an operating lever 30, pivoted at 31, at the end of a supporting bracket 32 therefor on the tank 1, the outer end of said operating lever being provided with a pull-chain or cord 33, preferably having a hand-grasp 34 at its lower end.

20 Supported in a suitable opening therefor in the bottom 2 of the tank 1, and having communication with the upper end of the flush-pipe 35, leading to the water-closet or other bowl, is the longer leg 36 of a siphon 37, 25 the shorter leg 38 of which terminates at its lower end a proper distance from said bottom 2, and, in order to supply air to the siphon at the end of the flushing operation I provide at one side of the end of said shorter leg 38 30 thereof, a downwardly extending vent-tube 39 communicating with the interior of such leg and reaching at its lower open end to within a short distance from the bottom of a cup 40, secured to the side of the leg, and the 35 sides of which extend upwardly to a suitable height about said vent-tube. During the flushing operation the vent-tube will act to siphon the water from said cup, as is apparent, and in consequence of which said vent-tube will remain open in fulfillment of its 40 function as such, until the water entering the tank again reaches a height at which it will overflow the said cup.

The water entering the casing 5 through 45 the nozzle or injector 9, is delivered to the tank by means of a delivery-pipe 41, leading from the lower section of said casing and having communication with the chamber 8 therein.

50 The parts being in the positions thereof indicated in full lines in Fig. 1, it is apparent that on pulling upon the pull-chain 33 with sufficient force the weighted member 20 will be elevated at its outer end, the movable connection 22 of the inner end of said member with the upper end of link 23 serving at this time as a fulcrum therefor. As said member 20 is thus elevated at its outer end, the pin or boss 19 thereof will be carried up to the horizontal 55 branch of the said angular slot 18 in the upper end of the lever 14, whereupon the pressure of water at the outlet of the nozzle or injector 9 at the upper end of the supply-pipe 4, assisted by the movement of member 60 20 forces the slidible block valve 10 out-

wardly in its seat within the valve casing, this action causing the said lever to swing inwardly within the tank, the said pin or boss now entering the said horizontal branch of said slot, it being apparent that the operations described are carried out practically simultaneously. As soon as the valve 10 is opened water enters the tank and rises therein to the height (indicated in dotted lines in Fig. 2) necessary to enable the siphoning to 75 take place, the float being caused to rise at the same time, as is apparent; and then, as the water leaves the tank through the longer leg of the siphon, the float and its connections fall with the water in the tank, as 80 shown in dotted lines, Fig. 1, the lever 14 and member 20 up to the time the float starts to fall, having remained practically in the positions to which they were first carried, with a new supply of water still entering the 85 tank. The opening of the valve 10 is limited by the engagement of the swinging lever 14 with the pin 45 in the arm 25. When the float 27 reaches its lowest position, as shown in dotted lines in Fig. 1, the weighted 90 lever 20 is retracted, as shown in dotted lines, until the pin 19 is above the vertical part of the slot 18. At this point the weight 21 causes the lever to move downward carrying the pin 19 into the vertical part of said 95 slot. As the float continues to be raised, the weighted lever is pushed outward carrying with it the swinging lever 14 until the valve 10 is closed.

The end of the said longer leg 36 of the 100 siphon enters a water trap 42 (which, however, may be located in the closet bowl itself), from which the pipe 35 leads to the bowl (not shown), and thus it will be understood that there will always be pressure in said leg 105 to prevent the siphoning operation from taking place until the water in the tank has attained a height considerably above the bend in the siphon.

Having thus described my invention, I 110 claim as new and desire to secure by Letters Patent:

1. A flushing device for water closet bowls and the like, comprising a tank, a siphon therein, a water supply pipe extending into the tank, a valve for opening and closing the water supply pipe, a swinging lever for operating the valve, a weighted lever for moving the swinging lever, a link pivoted to one end of the weighted lever, a rod having a float pivoted to the other end of the weighted lever and a pull lever connected with the link. 115

2. In flushing devices for water-closet bowls and the like, a tank, a water-supply pipe extending thereto, a valve for opening and closing the outlet for said pipe, and means for controlling the movements of said valve, comprising a swinging lever in direct movable connection with the valve, and a weighted member having independent mov- 120 125 130

able relation with said lever, the lever having an angular slot therein and the said member a portion working in the slot.

3. In flushing - devices for water - closet bowls and the like, a water-supply pipe extending thereinto, a valve for opening and closing the outlet for said pipe, and means for controlling the movements of the valve, comprising a swinging lever in movable connection with the valve, provided with an

angular slot, an operating lever, a weighted member having a pin working in said slot, a float, a link, and a rod therebetween.

In testimony whereof I have signed my name to this specification in the presence of 15 two subscribing witnesses.

LEWIS WATSON EGGLESTON.
